TWO-PIECE RAIL ANCHOR

John William Skeel, North Girard, Pa., assignor
to The American Fork & Hoe Company, Cleve-
land, Ohio, a corporation of Ohio

Application August 6, 1943, Serial No. 497,701

2 Claims. (Cl. 238—321)

My invention relates to rail anchors and relates more particularly to so-called "two-piece" rail anchors of the type having a rail base clamp and a spring projected therethrough and extending beneath the rail base to engage the opposite rail base edge to lock the anchor on the rail.

An object of my invention is to provide an improved rail anchor of the two-piece type which will be simple in application, inexpensive to manufacture and durable and efficient in use.

Another object of my invention is to provide an improved rail anchor of the two-piece type in which the spring may be driven into the clamp and locked on the rail base by a direct blow of the spike maul.

Another object of my invention is to provide an improved rail anchor of the two-piece type which will resist distortion in use.

Other objects of my invention and the invention itself will become increasingly apparent from a consideration of the following description and accompanying drawing, in which:

Fig. 1 is a side elevational view showing the improved rail anchor of my invention applied to the rail and abutting a cross tie;

Fig. 2 is a vertical sectional view taken on the line 2—2 of Fig. 1;

Fig. 3 is a vertical sectional view taken on the line 3—3 of Fig. 2;

Fig. 4 is a perspective view of the anchor clamp; and

Fig. 5 is a perspective view of the rail anchor spring member.

My invention may be considered as an improvement in certain respects over the two-piece anchors disclosed in patents to A. E. Fifield, Nos. 2,036,031 and 2,081,621, dated March 31, 1936, and May 25, 1937, respectively.

Referring now to the drawing, in which like parts are designated by like reference characters, at 10 I show a rail of conventional type having its rail flange 11 engaged by the rail anchor 12 of my invention. This rail anchor, as shown, consists of a substantially W-shaped clamp element 13 adapted to have a clip 14 projected through a perforation designated at 15 in Fig. 3 provided between the clamp 13 and the underside of the rail base 16 when the clamp is secured to the rail flange 11 and the clip projected through the clamp and under the rail base.

As illustrated herein, the clamp 13 is a generally W-shaped member having a pair of vertically extending generally parallel limbs 17—17 slightly bowed outwardly at 18 at their lower ends

and joined together at said ends by a web 19 integrally formed therewith.

The clamp web or seat 19, as best shown in Figs. 2 and 3, comprises a horizontally extending member 20 generally parallel to the base 16 of the member 13 and a hump 21 formed by bodily off-setting upwardly the center material of the forward end of the seat 19. The limbs 17—17 of the clamp are further provided with a pair of aligned notches 22—22, said notches being formed in the upper generally parallel disposed portions of the said limbs and conforming generally to the outer portion of the rail base flange 11, the notches initiating at the outer edge 23 of the upper portion of the limbs 17—17 slanting downwardly at 24 toward the center part of said limbs where the notches are disposed for a short distance generally parallel to the outer edge of the clamp as at 25 and are next disposed at right angles to the said edge 23, the bottom 24 of said notches disposed parallel to the member 20 of the clamp web 19.

As illustrated, the clamp is disposed vertically of the rail base and the outer edges of the clamp are parallel to the center line of the web of the rail, the bottom of the clamp being parallel to the bottom of the base of the rail.

The clip or spring member 14 projected through the perforation 15 provided by the engagement of the clamp with the rail, as best shown in Figs. 2 and 5, comprises a loop portion 30, an offset hook portion 31 at the opposite end of the clip and an intermediate arched member 32 joining the hook and loop portions. The clip 14 is preferably of a width slightly less than the width of the perforation 15 and the thickness of the clip at its point of engagement with the hump 21 is sufficient to compressively engage the hump, thereby maintaining the arched portion 32 of the clip under tension.

In applying the rail anchor, the notches 22—22 of the clamp engage the outer portion of the rail base flange, with one limb of the clamp abutting a tie, as shown in Fig. 1, the hook portion 31 and the arched portion 32 of the clip being projected through the perforation 15 and upon striking the loop portion 30 a direct blow with a spike maul, the loop is wedged over the hump 21 and the hook 31 sprung over the opposite edge of the rail base flange, locking the anchor in position.

It will be noted that, with the improved rail anchor of my invention, the base at the bottom of the clamp is in a horizontal rather than in an angular position, as in prior art patents to which I have previously referred.

It will further be noted that the loop portion of the clip or spring member has an upper surface of the loop, as shown at *x*, provided with a flat portion which is adapted to be disposed horizontally with respect to the bottom of the rail base which it engages, and that the lower portion of the loop is also provided with a flat portion, as shown at *y*, which engages the flattened upper surfaces of the hump *21* whereby, upon load being applied to the rail as the rail tends to move downwardly relative to the clamp shoe *13*, the loop portion abutting the hump *21* tends to increase the canting action of the clamp *13* on the rail base flange ensuring positive clamping action irrespective of load commissions.

An advantage accruing from the improved positioning of the clamp and clip member of my present invention further resides in the fact that the said anchor will give more improved action in frozen ballast than in anchors of the prior art. In connection with prior art devices, it has been found that, where the ballast is not particularly clean and there is insufficient drainage, the same freezes into a solid form and normally, upon the application of loads to the rail, the angularly disposed clamp has a tendency to distort and be forced outwardly.

Although I have shown and described the preferred embodiment of my invention, I am aware that numerous and extensive departures may be made therefrom without however departing from the spirit of the invention and the scope of the appended claims.

I claim:

1. A two-piece rail anchor comprising a spring member having an intermediate arched portion adapted to underlie the base of a rail, an upwardly disposed hook end portion engageable with a rail flange edge and a downwardly disposed loop portion at its opposite end, a generally channel shaped clamp member of substantially W-shaped form, said clamp comprising a pair of vertically extending spaced limbs, said limbs having a portion of each disposed generally parallel to each other and each comprising a lower portion, said lower portions being generally bowed with respect to each other, a web portion connecting said upwardly extending limbs, said web comprising a horizontally extending member and a hump portion, said hump being disposed in the forward portion of the web and offset with respect

to the horizontally extending portion thereof, a notch disposed in each of the limbs, said notches conforming in shape to the conformation of the outer portion of the rail flange, the clamp in operation being disposed vertically of the rail base, the outer edges of the clamp being parallel to the center line of the web of the rail, the horizontally extending portion of the web of the clamp being parallel to the bottom of the base of the rail, the spring member being projected through the space provided between the limb portions of the clamp below the notch portions of the limbs and above the web of the clamp, the hook portion being projected through said clamp initially, the intermediate portion of the spring member underlying the base of the rail, the loop being in wedged contact with the offset hump of the clamp and one rail flange being wedged within the aligned notches disposed in the limb members and the opposite rail flange edge being engaged by the hooked end portion of the clamp whereby the anchor is locked in position with the rail.

2. A two-piece rail anchor comprising a spring member having a hook end portion, a loop portion and a connecting portion disposed between said hooked end and loop portions, and a clamp member of generally channel shaped form, said clamp member comprising a pair of upwardly extending limbs, said limbs having aligned notches disposed in the forward faces of the same and a web portion having an intermediate upstanding hump portion, said hump portion initiating in the central portion of the web portion and being progressively more offset with respect to the remainder of the web portion as said hump approaches the forward end of the clamp, the spring member being inserted through the clamp member between the limbs thereof, its hooked end portion being lockingly engaged with a rail flange, the connecting portion underlying the rail base and the loop portion wedgingly engaged with said offset hump portion, the said clamp being locked in engagement with a rail flange disposed on the opposite side of the said rail from said first named flange, said notches receiving the said second flange, said clamp being disposed vertically of the rail base, the outer faces of the clamp being parallel to the center line of the web of the rail.

JOHN WILLIAM SKEEL.
